Patented Feb. 3, 1920.

Inventor.

G. D. Maxson.

By *Herbert E. Peck* Attorney.

UNITED STATES PATENT OFFICE.

GEORGE D. MAXSON, OF WEST EDMESTON, NEW YORK.

ICE-CREEPER.

1,329,987.

Specification of Letters Patent.

Patented Feb. 3, 1920.

Application filed January 17, 1919. Serial No. 271,690.

To all whom it may concern:

Be it known that I, GEORGE D. MAXSON, a citizen of the United States of America, and resident of West Edmeston, Otsego 5 county, State of New York, have invented certain new and useful Improvements in Ice-Creepers, of which the following is a specification.

This invention relates to certain improvements in antislipping devices or so-called ice creepers; and the objects and nature of the invention will be readily understood by those skilled in the art in the light of the following explanation of the accompanying 15 drawings illustrating what I now believe to be the preferred embodiment or mechanical expression of my invention from among other forms, constructions and arrangements within the spirit and scope thereof.

20 An object of the invention is to provide an ice creeper that can be sold at a moderate price, will be simple and durable in construction, and capable of easy application to and removal from foot wear heels of 25 different shapes and dimensions, and of such retractile elastic formation and construction as to surround and tightly grip and embrace the heel against accidental displacement therefrom and to maintain one or more 30 calks properly positioned on the heel.

With these and other objects in view the invention consists in certain novel features in construction and in combinations and arrangements as more fully and particularly 35 set forth and specified hereinafter.

Referring to the accompanying drawings:—

Figure 1, is a perspective view showing an embodiment of my invention in operative 40 position on a foot wear heel.

Figs. 2 and 3 are different views of the ice creeper.

In the drawings, I show any suitable foot wear (boot, shoe or the like) heel *a* with an 45 ice creeper of my invention applied thereto and in operative position thereon.

The ice creeper of my invention consists of a contractile elastic ring, annulus or closed loop formed to encircle the heel and, 50 in a measure, conform to the shape thereof and so grip the vertical walls of the heel as to maintain its position on the heel against accidental displacement therefrom, and this contractile ring carries calk means as an in- 55 tegral (inseparable) part thereof and ar-

ranged to underlie and be backed by the bottom or wear surface of the heel.

In the particular embodiment illustrated, the contractile ring or annulus consists of a length of cylindrical contractile flexible 60 coiled wire spring 1, and a stirrup, in this instance, composed of a length of comparatively stiff spring wire 2 bent into approximately **U** shape with the ends of the **U** permanently secured to the ends of the contractile coiled spring 1. The end portions of the spring wire length 2 are thus permanently connected by the longitudinally contractile flexible spring length to complete the ring or closed loop. The stiff wire 70 length 2 is bent to provide and form the calk means. For instance, in the particular example illustrated, this wire is bent to form a pair of opposite angle arms depending from the ends of the legs of the **U** and carrying calks. Each arm consists of an approximately straight length 20 perpendicular to the general plane of the ring and a free end length 21 extending laterally from and approximately at right angles to length 80 20 in a plane approximately parallel with said plane of the ring and terminating in a downturned point or extremity forming the calk 22. The structure and arrangement is such that when the ring encircles the heel in operative position, the arm portions 20 will depend at opposite edge portions of the heel with the arm portions 21 extending toward each other along the wear or bottom surface of the heel and the calks 22 spaced 90 apart and depending from approximately the central portion of the wear surface of the heel to perform the well understood functions of biting into or "taking hold" of slippery surfaces to prevent slipping. 95

The angle or calk carrying arms 20—21 are preferably arranged approximately midway between the front and rear ends of the heel. The stiff wire is bent to approximate **U** shape to form a portion of the annulus of 100 the complete ring and to fit and approximately conform to the shape of one end portion of a heel. The resiliency or elasticity of the stiff wire tends to maintain the wire yieldingly in its original **U** shape and 105 to return the wire to such shape when distorted therefrom. The **U** shape wire is hence contractile *i. e.* the **U** can be expanded or spread against the resiliency of the wire and will return to original position when re- 110

leased. The **U** shaped wire can hence spread to conform to or fit heels varying considerably in size and shape and will grip the edge walls of such heels under tension. The 5 coiled contractile spring is expansible in length to receive heels varying greatly in size and is flexible laterally to conform to the shape of the heels and tightly grip edge walls thereof under tension. By combining 10 the contractile coiled spring with the wire length (carrying the calk means) to form a contractile ring or annulus, the ice creeper is adaptable to and will maintain its operative position on heels differing greatly in 15 size and shape, and yet the creeper can be easily applied to and removed from such heels. The coiled wire spring constitutes means by which the annulus can be conveniently stretched and manipulated in applying the creeper to the heel, particularly 20 as the spring will readily slip up on the heel on the final creeper applying movement. The coiled spring also maintains a firm friction or biting grip on the edges of the heel 25 and holds the **U** wire closed longitudinally against the heel end. The coiled spring also serves as a hand hold for the manipulation of the creeper in the initial releasing movement thereof from the heel.

30 In practice, one size of ice creeper is adaptable for approximately all sizes and shapes of heels found on men's boots and shoes, while a different size of ice creeper is adaptable for approximately all the heels of ladies' 35 out of door footwear.

It is evident that various changes, modifications and variations can be resorted to

without departing from the spirit and scope of my invention and hence I do not wish to limit myself to the exact disclosures hereof. 40

What I claim is:—

1. An ice creeper composed of an elastic contractile heel gripping annulus embodying a resilient stirrup, its legs tending to spring laterally to normal position whereby said 45 stirrup is rendered contractile in width to fit the edge walls of heels of different widths and tightly grip the same, said legs carrying and provided with depending arms arranged to engage opposite edge walls of the heel between the front and rear ends thereof, said depending arms being turned laterally and inwardly at their lower ends to fit under the heel and equipped with calk means, the arms of said stirrup being disconnected one from 50 the other except through the legs of said stirrup.

2. An ice creeper composed of an elastic contractile annulus formed and constructed to surround a heel and grip the edge walls 60 thereof, said annulus embodying and including a resilient laterally contractile stirrup formed to partially embrace the heel and grip the edge walls thereof, the opposite legs of said stirrup being each provided with 65 and carrying an independent angle arm formed to depend at the edge of the heel between the front and rear ends thereof and extend therefrom inwardly under the heel and provide calk means, and a contractile 70 spring fixed to and joining the legs of the stirrup to embrace the remainder of the heel and grip the edge walls thereof.

(Signed) GEORGE D. MAXSON.
